United States Patent Office.

JOHN H. BELLAMY, OF CHARLESTOWN, MASSACHUSETTS, ASSIGNOR TO HIMSELF AND D. A. TITCOMB, OF SAME PLACE.

Design No. 2,543, dated January 8, 1867.

DESIGN FOR A BRACKET.

The Schedule referred to in these Letters Patent and making part of the same.

TO WHOM IT MAY CONCERN:

Be it known that I, JOHN H. BELLAMY, of Charlestown, in the county of Middlesex, and State of Massachusetts, have invented a new and improved Design for a Bracket; and I hereby declare that the following is an exact and full description thereof, reference being had to the accompanying photographs, and to the letters of reference marked thereon.

My invention consists of a design for a bracket composed of emblematic symbols, so arranged as to produce an open-work design, as follows, to wit: Above the shelf A is a scroll, 1, with a pen, 2, passing through its top; a broken chain, 3, with the separated links resting upon said scroll, the chain extending on either side of it and connecting with ornamental scroll-work, which forms the outline of the bracket. Above the scroll 1 is a picture frame, 4, surmounted by a wreath, 5, both being enclosed and supported by the aforesaid outline scroll-work. Beneath the shelf A is a shield, 6, with a flag, 7, on either side of it. Attached to the shield 6 is a support to the shelf A with a star, 8, set in it. The whole substantially as shown in the photograph.

What I claim as invention, and desire to secure by Letters Patent, is—

The design for a bracket, substantially as shown and described.

JOHN H. BELLAMY.
